(57) **CLAIM**

The ornamental design for a gardening implement, as shown and described.

DESCRIPTION

FIG. 1 is a top, perspective view of the gardening implement;

FIG. 2 is a top plan view thereof;

FIG. 3 is a bottom plan view thereof;

FIG. 4 is a right side elevation and a mirror image of the left

side elevation thereof;

FIG. 5 is a front elevation view thereof; and,

FIG. 6 is a rear side elevation view thereof.

The broken lines represent portions of the article and form no

part of the claimed design.
